(57) **CLAIM**

The ornamental design for an ultraviolet irradiator, as shown and described.

DESCRIPTION

FIG. 1 is a top, front, right perspective view of an ultraviolet irradiator, showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The present article is a portable ultraviolet ray irradiator. An ultraviolet ray light source is located inside of the ultraviolet ray irradiator, and ultraviolet rays pass through an irradiation portion shown in the “reference perspective view showing a name of each part and a transparent portion” and are irradiated to the exterior of the present article.

The shading in the white portions, other than black portions and the transparent portion, represented on the entirety of the surfaces in each figure is for specifying the shape of the three-dimensional surfaces. Light and dark portions created by reflection of light that appear in parts of each figure are not elements of the design. The irradiation portion represented in light blue in the reference perspective view showing a name of each part and a transparent portion is transparent.

1 Claim, 7 Drawing Sheets
